UNITED STATES PATENT OFFICE

GEORGE F. HANDLEY, OF GLENDALE, AND LEWIS C. MYERS, OF FREEPORT, NEW YORK,
ASSIGNORS TO ROYAL TYPEWRITER COMPANY, INC., OF NEW YORK, N. Y., A COR-
PORATION OF NEW YORK

TYPEWRITING MACHINE

Application filed June 29, 1931. Serial No. 547,694.

This invention relates to new and useful improvements in manifolding attachments for typewriting machines or the like, and embodies certain improvements over our co-pending application Serial No. 546,858, filed June 25, 1931, relative to the tensioning means for the ribbon spools, the manually actuated locking means for the spools, and the manually actuated means for withdrawing the tensioning means and the locking means away from the spools a distance sufficient to permit of the spools being readily removed from or applied to their supporting shaft without any interference.

15 Among the several objects of this invention are to provide novel means for supporting ribbon spools on the machine, peripheral members connected to the respective spools for rotation therewith, a constant spool tensioning means and a normally ineffective locking means cooperating with the periphery of each member, and means to render said locking means effective during the feeding movement of the carbon strips or ribbons 20 and preferably prior to the completion thereof whereby the last portion of the ribbon feeding movement will remove all slack in the ribbon immediately prior to the line spacing operation of the work sheets; to 25 provide a manually operable means for releasing all tensioning and locking means simultaneously whereby the spools may be readily positioned on their supporting shaft or removed therefrom without interference, and to 30 provide a ribbon spool assembly of the character described which can be readily and cheaply manufactured and easily applied to a typewriting machine of the construction illustrated in the co-pending application re- 35 ferred to above.

With these and other objects in view which will more fully appear, the nature of the invention will be more clearly understood by following the description, the appended 40 claims, and the several views illustrated in the accompanying drawings.

In the drawings:—

Figure 1 is a vertical sectional view of a typewriting machine showing in elevation 45 the application of the invention,

Figure 2 is a rear view thereof, parts of the typewriting machine being omitted to better disclose the invention,

Figure 3 is a top plan view of the structure shown in Figure 1, parts of the main frame and the carriage being omitted,

Figure 4 is a vertical sectional view through the spool supporting frame showing the tension means and the locking pawl in operative positions,

Figure 5 is a vertical sectional view taken on the line 5—5 of Figure 4,

Figure 6 is a horizontal sectional view taken through the spool supporting frame,

Figure 7 is a detail vertical sectional view 65 showing the tension means and the clutch pawl in released positions,

Figure 8 is a perspective view of one of the levers which carries the tension rolls,

Figure 9 is a sectional view of the assembled lever and tension roller,

Figure 10 is a perspective view of one of the locking levers,

Figure 11 is a horizontal section taken on the line 11—11 of Figure 4, and

Figure 12 is a rear elevation of the spool supporting frame.

As previously stated, this invention relates to improvements in the ribbon spool tensioning and locking means shown in our application filed June 25, 1931, and therefore only that much of the typewriting machine is illustrated in the drawings as will be necessary to an understanding of the present invention.

The typewriting machine includes a main frame A on which a carriage B is supported for letter space movements. A platen C is fixed to the lower end of a collating frame D pivoted on the carriage to swing forwardly and rearwardly to effect a rearward and forward movement of the platen upon swinging movement of the carriage return lever E through suitable connections shown in our co-pending application. Type bars F cooperate with the platen, and a main ribbon G is disposed in front of the platen. Work sheets H are led forwardly to the platen over a work guide I attached to the carriage, thence over a roller 5 journaled on the carriage, thence downwardly under a guide roller 6 journaled 100

on the carriage below the platen, and thence upwardly past the platen and have their upper edge portions clamped to a truck J which is mounted on the collating frame D for line space movements, the truck being line spaced by the lever E by a mechanism shown in our copending application. A spool supporting frame K is disposed in rear of the main frame A and is attached to the carriage to move therewith, the frame K carrying rollers 7, 7 which ride along a rail 8 attached to the main frame A. A plurality of ribbon spools L are rotatably supported on a shaft 9 fixed to the frame K, and the carbon strips or ribbons M are led from the spools forwardly along the left side of the carriage, thence along and in front of the platen and in rear of the main ribbon G and in interleaved relation with the work sheets, and thence rearwardly along the right hand side of the carriage to a ribbon feeding means N which includes cooperating feed rolls 10, 10. The ribbon feeding means N is actuated from the collating frame D by connections shown in our copending application. Means are provided for individually and normally tensioning the spools against feeding rotation and other means which are normally ineffective, are provided for individually and simultaneously locking the spools against feeding rotation at a period of time immediately before the ribbon feeding means has completed its movement whereby the ribbons will be rendered taut before the work sheets are line spaced thereby preventing the carbon strips from being dragged upwardly therewith. Means are also provided for simultaneously releasing the tensions and the clutch pawls whereby the spools may be readily removed from or applied to the spool supporting shaft without any interference.

The above construction is shown and claimed in our co-pending application, and the present invention relates to a different tensioning and locking means for the spools and to means for releasing the same from the spools.

The spool supporting frame K includes front and rear walls or plates 11 and 12 respectively, which are rigidly connected by spaced upper side braces 13, 13 and spaced lower side braces 14, 14, the latter being provided with upstanding flanges 14^a, 14^a along their outer side edges thereof. The spool supporting shaft 9 is fixedly secured at its front end to the front plate 11 and the rear free end of the shaft is located centrally with respect to an opening 15 formed in the rear plate 12, the opening being of a size sufficient to permit a ribbon spool L to be freely passed therethrough.

Each spool L comprises a hub 16 having a disc member 17 fixed thereto and provided with a serrated clutch periphery 18. Mounted on the hub 16 is a core 19 having a trans-

verse opening or seat 20 which receives a pin 21 fixed to the disc member 17, to maintain the core and disc against relative rotation yet permitting of the core being removed from the hub or positioned thereon.

Disposed directly below the horizontal spool shaft 9 is a horizontal bearing rod 22 having its ends secured to the front and rear plates 11 and 12, the rod being disposed in a horizontal plane below the opening 15 of the rear plate. Disposed above the rod 22 and below the spools L is an arcuate plate 23 which is sprung into place against the lower side braces 14, 14, and is concentric with the axis of the spool supporting shaft 9. The plate 23, as viewed in Figure 7, is provided along its side edges with depending flanges 23^a and 23^b respectively, the former being flat throughout its height, and the latter being formed with an inwardly curved lower end portion 23^c. When positioning the plate 23 on the braces 14, 14, the flange 23^a of the plate is first positioned against the inner face of the flange 14^a of the associated brace 14, and then the other flange 23^b is pushed downwardly and sprung into place against the flange 14^a of the other brace 14, the lower curved portion 23^c facilitating the operation. Thus the plate 23 is yieldably but firmly retained in position on the braces 14, 14. A series of openings 24 and a series of openings 25 are respectively formed in the arcuate plate 23 on opposite sides of the rod 22, and are disposed in parallelism therewith. These openings are arranged in pairs, one opening 24 and one opening 25 being in register with the disc member 17 of each spool L. Associated with each opening 24 is a tension lever O which is in the nature of a bell crank lever and includes spaced parallel members of identical construction, each member comprising a depending cam arm 26 and a horizontal arm 27, the latter terminating in an upstanding arm 28, and both arms 28 being connected by a web 29. The lever O is journaled on the bearing rod 22, there being alined bearing openings 30, 30 formed in the horizontal arms 27, 27 adjacent the depending cam arms 26, 26 for receiving the bearing rod. The upstanding arms 28, 28 are provided adjacent their upper ends with alined bearing openings 31, 31 to receive the hub 32 of a friction roller 33 having a serrated periphery 34, the hub and roller being in tight contact to rotate in unison. The hub is also slidable in the bearing openings 31, 31, and one end of the hub projects beyond the adjacent arm 28 and is formed in its extreme end with a conical recess 35 which forms a resultant circular friction surface 36. A flat spring which is attached to the arm 28 at its lower end by a rivet 37, has its upper end bearing against the friction surface 36 which causes the roller to frictionally engage the inner face of the other arm 28 as shown in Figure 9. Thus the

rotation of the roller 33 is resisted by two frictional brakes, the first being located between the circular surface 36 of the hub and the upper end of the spring, and the second being located between the roller 33 and the arm 28 opposite the spring. These serrated rollers 33 are yieldably retained in engagements with the serrated peripheries 18 of the disc members 17 by coil springs 38, and the feeding rotations of the spools are individually resisted by the two frictional brakes above noted.

A plurality of lock levers P are also fulcrumed on the bearing rod 22, there being one lever for each spool. Each locking lever P is in the nature of a bell crank lever consisting of a depending cam arm 39, a horizontal arm 40, and a locking pawl 41 which is integral with the horizontal arm and extends upwardly therefrom and between the ends thereof. The serrations 34 of the friction rollers 33, the serrations 41^a of the pawls 41, and the serrations 18 of the discs 17 are consistent with one another, and consequently the pawls will fit the discs for positive locking contact therewith, and the rollers will have positive intermeshing engagements with the discs and therefore there will be no slippage between them. The horizontal arm 40 is formed adjacent the depending arm with a bearing opening 42 for receiving the bearing rod 22. Each lock lever P is located between the spaced bell crank members of the associated tension lever O with the pawl 41 disposed on the side of the bearing rod 22 opposite the tension roller 33, and with the depending cam arm 39 on the side of the bearing rod opposite the depending cam arm 26 of the tension lever. A plurality of spacing sleeves 43 are journaled on the bearing shaft intermediate the lock levers P and function to maintain the same in register with the respective disc members 17.

Disposed directly below and in parallelism with the bearing rod 22 is a cam shaft 44 which is journaled at its ends on the front and rear walls or plates 11 and 12 of the spool frame K. This shaft is provided with opposite and parallel cam faces 45, 45, and the shaft extends between depending cam arms 26 of the tension levers O and the depending cam arms 39 of the lock lever P.

Each spring 38 which is connected at one end to one of the upstanding arms 28 of the tension lever O, has its other end connected to the associated pawl 41 and functions not only to yieldably retain the tension roller 33 in contact with the periphery 18 of the disc 17, but also to urge the pawl 41 into contact with said periphery 18.

However, the pawls 41 are normally ineffective and are held against normally engaging the peripheries 18 of the discs 17, by a bail which includes a universal bar 46 common to all of the lock levers P. This univer-

sal bar 46 is disposed directly above the outer ends of the horizontal arms 40 of the lock levers and is pivotally supported on the ends of the bearing rod 22 through the medium of a rock arm 47 and a lever 48. The end of the lever 48 opposite the universal bar is connected to one end of a coil spring 49, the other end of the spring being anchored to the adjacent lower side brace 14 of the spool frame. The tensile strength of this spring 49 is greater than the combined tensile strength of all the springs 38, and consequently the universal bar 46 is yieldingly pulled downwardly against the horizontal arms 40 of the lock levers O and the pawls 41 are thereby normally held out of contact with the peripheries 18 of the discs 17 as shown in Figure 2.

One end of each spring 38 is attached to the upper end of the arm 28 of the tension lever O in order to give maximum tension between the friction roller 33 and the disc 17, and the other end of the spring is attached to the lower end of the associated pawl 41 in order to give a minimum tension to the lock arm P to permit easy release of said arm from the disc 17, thereby not only rendering the spring 49 most effective but also minimizing the effort required to release the pawls from the discs.

In order to lift the universal bar 46 upon swinging of the carriage return lever E and thereby permit the springs 38 to effect locking engagement between all of the pawls 41 and all of the associated discs 17, a bell crank lever 50 is fulcrumed on the front wall or plate 11 directly above the spool shaft 9. The horizontal arm 51 of the lever is disposed directly above the lever 48 and is connected thereto by a link 52. The upwardly extending arm 53 of the lever is pivotally connected to one end of a link 54, the other end of the link being pivotally connected to one arm of a bell crank lever 55 which is fulcrumed on the carriage B at the left hand end thereof. A link 56 is pivotally connected at its rear end to the other arm of the bell crank lever 55 and the front end of the link is pivotally connected to one arm of a bell crank lever 57, the other arm of the lever being disposed in cooperative relation to a cam head 58 fixed to the carriage return lever E. Parts corresponding to the link 54, bell crank lever 55, link 56, bell crank lever 57, cam head 58, and carriage return lever, are all fully described in our co-pending application referred to above.

Fixed to the rear end of the cam shaft 44 is an upwardly extending lever arm 59 which terminates at its upper end in a rearwardly extending finger piece 60. Formed in the lever arm 59 below the finger piece is an opening or seat 61 for receiving the reduced rear end 62 of the spool supporting shaft 9 and thereby provide a support for the rear free

end of said shaft 9. This lever arm 59 is adapted to be retained in its normal position against accidental disengagement from the shaft 9 by means of a spring plunger 63 mounted in a barrel 64 which extends rearwardly from the lever arm 59, the plunger having its front end normally located in an opening or seat 65 formed in the rear wall 12 of the spool supporting frame K. This lever arm 59 has the additional function to rock the cam shaft 44 and thereby simultaneously withdraw or retract all of the tensioning means from their cooperative engagements with the serrated surfaces 18 of the spool discs 17, and to also further retract simultaneously all of the locking pawls 41, as shown in Figure 7. Thus upon manipulation of the lever 59, the serrated edges of the clutch pawls 41 and the serrated surfaces 20 of the friction rollers 33, are lowered to positions below the arcuate plate 23, thereby permitting the spools L to be readily removed from or applied to the shaft 9 without interference whatsoever.

25 In the operation of our invention, the work sheets H are loaded into the machine and the carbon strips or ribbons M are interleaved therewith in front of the platen C and the free ends of the ribbons are engaged between 30 the feed rolls 10, 10 of the feeding means N, after which the lead-in ends of the work sheets are clamped to the truck J. The operator then writes a line on the work sheets. The carriage return lever E is then swung to 35 the right, prior to returning the carriage, and during the first part of the swinging movement of the lever, the collating frame D is swung forwardly and the platen C rearwardly to relieve the normal tight contact relation 40 between the work sheets and the platen. The ribbon feeding means N is actuated simultaneously with the forward movement of the collating frame, and thus the carbon ribbons M are fed against the individual tensioning 45 means which are constantly applied to the ribbon spools. Prior to the completion of the operation of said feeding means, the locking means for the respective spools is rendered effective, thereby permitting the last part of 50 the movement of the feeding means to stretch the ribbons fully taut whereby they will not be dragged upwardly with the work sheets during the line spacing movement thereof.

55 During the last part of the swinging movement of the carriage return lever to the right, the truck J is moved upwardly along the collating frame for the desired distance to properly line space the work sheets. The operator then, by a continued pressure on the lever 60 towards the right, returns the carriage to its initial or desired position, and upon release of the lever the previously moved parts, except the truck J, will return to their normal 65 positions.

We claim:—

1. In a manifolding typewriter, the combination with a carriage having a platen past which a work sheet is fed, a ribbon spool journaled on the carriage, ribbon feeding means mounted on the carriage, means for guiding the ribbon from the spool across the work sheet to said feeding means, a member connected to the ribbon spool to rotate therewith and provided with a serrated periphery, means cooperating with the periphery of said member for tensioning the feeding movement of the ribbon, normally ineffective locking means adapted to cooperate with the periphery of the member to retain the spool against rotation, and means for actuating the ribbon feeding means and concomitantly rendering said locking means effective. 70

2. In a manifolding typewriter, the combination with a carriage having a platen past which a work sheet is fed, a non-rotatable shaft fixed to the carriage, a ribbon spool journaled on said shaft, a peripheral member rotatable about said shaft and connected to the spool to rotate therewith, ribbon feeding means mounted on the carriage, means for guiding the ribbon from the spool across the work sheet to said feeding means, means cooperating with the periphery of the member for tensioning the feeding movement of the ribbon, normally ineffective locking means adapted to cooperate with the periphery of the member to retain the spool against rotation, and means for actuating the ribbon feeding means and concomitantly rendering said locking means effective. 90

3. In a manifolding typewriter, the combination with a carriage having a platen past which a work sheet is fed, a non-rotatable shaft fixed to the carriage, a ribbon spool journaled on said shaft, a peripheral member rotatable about said shaft and connected to the spool to rotate therewith, said member being provided with a serrated surface arranged concentrically with respect to the shaft, ribbon feeding means mounted on the carriage, means for guiding the ribbon from the spool across the work sheet to said feeding means, means cooperating with the serrated surface of the member for tensioning the feeding movement of the ribbon, normally ineffective locking means adapted to co-operate with the serrated surface of the member to retain the spool against rotation, and means for actuating the ribbon feeding means and concomitantly rendering said locking means effective. 105

4. In a manifolding typewriter, the combination with a carriage having a platen past which a work sheet is fed, a ribbon spool journaled on the carriage, ribbon feeding means mounted on the carriage, means for guiding the ribbon from the spool across the work sheet to said feeding means, a member connected to the ribbon spool to rotate therewith and provided with a serrated periphery, 110

ing the ribbon feeding means and concomitantly rendering said locking means effective, and manually operable means for releasing the tensioning means from the serrated member and for simultaneously further retracting the locking means.

10. In a manifolding typewriter, the combination with a carriage having a platen past which a work sheet is fed, a ribbon spool journaled on the carriage, ribbon feeding means mounted on the carriage, means for guiding the ribbon from the spool across the work sheet to said feeding means, a member connected to the ribbon spool to rotate there-with and provided with a serrated periphery, means cooperating with the periphery of said member for tensioning the feeding movement of the ribbon, normally ineffective locking means adapted to cooperate with the periphery of the member to retain the spool against rotation, means for actuating the ribbon feeding means and concomitantly rendering said locking means effective, and means including a manually rockable cam shaft for releasing the tensioning means from the serrated member and for simultaneously further retracting the locking means.

11. In a manifolding typewriter, the combination of a carriage having a platen past which work sheets are fed, a non-rotatable shaft fixed to the carriage, a plurality of ribbon spools journaled on said shaft, peripheral members respectively disposed intermediate said spools and respectively connected thereto for rotation therewith, ribbon feeding means mounted on the carriage, means for guiding the ribbons from the spools across the work sheets and interleaved therewith to said feeding means, separate means cooperating with the peripheries of the members for tensioning the feeding movements of the ribbons, a plurality of normally ineffective locking means adapted to respectively cooperate with the peripheries of the members to retain the spools against rotation, means for actuating the ribbon feeding means and concomitantly rendering said locking means effective, and manually operable means for simultaneously releasing all tensioning means from engagements with said members.

12. In a manifolding typewriter, the combination of a carriage having a platen past which work sheets are fed, a non-rotatable shaft fixed to the carriage, a plurality of ribbon spools journaled on said shaft, peripheral members respectively disposed intermediate said spools and respectively connected thereto for rotation therewith, ribbon feeding means mounted on the carriage, means for guiding the ribbons from the spools across the work sheets and interleaved therewith to said feeding means, separate means cooperating with the peripheries of the members for tensioning the feeding movements of the ribbons, a plurality of normally ineffective

locking means adapted to respectively cooperate with the peripheries of the members to retain the spools against rotation, means for actuating the ribbon feeding means and concomitantly rendering said locking means effective, a rockable cam shaft located beyond the peripheries of the members and disposed in parallelism with the spool-supporting shaft, operative connections between the tensioning means and the cam shaft and between the locking means and the cam shaft, and a manually operable hand lever fixed to the cam shaft for rocking the same to effect a simultaneous release of all tensioning means.

13. In a manifolding typewriter, the combination of a carriage having a platen past which work sheets are fed, a non-rotatable shaft fixed to the carriage, a plurality of ribbon spools journaled on said shaft, peripheral members respectively disposed intermediate said spools and respectively connected thereto for rotation therewith, ribbon feeding means mounted on the carriage, means for guiding the ribbons from the spools across the work sheets and interleaved therewith to said feeding means, separate means cooperating with the peripheries of the members for tensioning the feeding movement of the ribbons, comprising a plurality of levers, a serrated roller journaled on each lever for engaging the serrated periphery of the associated member, and springs respectively connected to the levers for retaining the rollers in tensioning engagements with said member, normally ineffective locking means adapted to respectively cooperate with the peripheries of the members to retain the spools against rotation, means for actuating the ribbon feeding means and concomitantly rendering said locking means effective, a rockable cam shaft located beyond the peripheries of the members and disposed in parallelism with the spool-supporting shaft, operative connections between the roll-carrying levers of the tensioning means and the cam shaft and between the locking means and the cam shaft, and a manually operable hand lever fixed to the cam shaft for rocking the same to effect a simultaneous release of all tensioning means.

14. In a manifolding typewriter, the combination with a carriage having a platen past which a work sheet is fed, of a collating frame fulcrumed on the carriage to swing forwardly from a normally rearwardly inclined position and forming a support for the platen whereby the latter will be bodily moved rearwardly simultaneously with the forward swinging of the frame, a ribbon spool journaled on the carriage, ribbon feeding means mounted on the carriage, means for guiding the ribbon from the spool across the work sheet and in front of said platen to said feeding means, a peripheral member connected to the ribbon spool to rotate therewith and pro-

vided with a serrated periphery, means co-operating with the periphery of said member for tensioning the feeding movement of the ribbon, normally ineffective locking means adapted to cooperate with the periphery of the member to retain the spool against rotation, and means including a single manually operable lever for swinging the collating frame forwardly and the platen rearwardly, for actuating the ribbon feeding means, and for rendering the ribbon locking means effective.

15. In a manifolding typewriter, the combination with a carriage having a platen past which a work sheet is fed, of a collating frame fulcrumed on the carriage to swing forwardly from a normally rearwardly inclined position and forming a support for the platen whereby the latter will be bodily moved rearwardly simultaneously with the forward swinging of the frame, a ribbon spool journaled on the carriage, ribbon feeding means mounted on the carriage, means for guiding the ribbon from the spool across the work sheet and in front of said platen to said feeding means, a peripheral member connected to the ribbon spool to rotate therewith and provided with a serrated periphery, means co-operating with the periphery of said member for tensioning the feeding movement of the ribbon, normally ineffective locking means adapted to cooperate with the periphery of the member to retain the spool against rotation, and means including a single manually operable lever for swinging the collating frame forwardly and the platen rearwardly, for actuating the ribbon feeding means, and for rendering the ribbon locking means effective prior to the completion of the ribbon feeding movement.

16. In a manifolding typewriter, the combination with a carriage having a platen past which a work sheet is fed, of a collating frame fulcrumed on the carriage to swing forwardly from a normally rearwardly inclined position and forming a support for the platen whereby the latter will be bodily moved rearwardly simultaneously with the forward swinging of the frame, a ribbon spool journaled on the carriage, ribbon feeding means mounted on the carriage, means for guiding the ribbon from the spool across the work sheet and in front of said platen to said feeding means, a peripheral member connected to the ribbon spool to rotate therewith and provided with a serrated periphery, means co-operating with the periphery of said member for tensioning the feeding movement of the ribbon, normally ineffective locking means adapted to cooperate with the periphery of the member to retain the spool against rotation, connections between the collating frame and the ribbon feeding means for actuating the latter upon forward swinging movement of the former, and means including a single

manually operable lever for swinging the collating frame forwardly and the platen rearwardly and for rendering the ribbon locking means effective prior to the complete forward movement of the collating frame and the completion of the feeding action of said feeding means.

17. In a manifolding typewriter, the combination of a carriage having a platen past which work sheets are fed, a non-rotatable shaft fixed to the carriage, a plurality of ribbon spools journaled on said shaft, peripheral members respectively disposed intermediate said spools and respectively connected thereto for rotation therewith, ribbon feeding means mounted on the carriage, means for guiding the ribbons from the spools across the work sheets and interleaved therewith to said feeding means, separate means cooperating with the peripheries of the members for tensioning the feeding movements of the ribbons, a plurality of normally ineffective locking means adapted to respectively cooperate with the peripheries of the members to retain the spools against rotation, and means for actuating the ribbon feeding means and concomitantly rendering said locking means effective.

18. In a manifolding typewriter, the combination of a carriage having a platen past which work sheets are fed, a non-rotatable shaft fixed to the carriage, a plurality of ribbon spools journaled on said shaft, peripheral members respectively disposed intermediate said spools and respectively connected thereto for rotation therewith, ribbon feeding means mounted on the carriage, means for guiding the ribbons from the spools across the work sheets and interleaved therewith to said feeding means, separate means cooperating with the peripheries of the members for tensioning the feeding movement of the ribbons, comprising a plurality of levers, a serrated roller journaled on each lever for engaging the serrated periphery of the associated member, and springs respectively connected to the levers for retaining the rollers in tensioning engagements with the members, normally ineffective locking means adapted to respectively cooperate with the peripheries of the members to retain the spools against rotation, and means for actuating the ribbon feeding means and concomitantly rendering said locking means effective.

19. In a ribbon spool assembly, the combination with a supporting frame, of a non-rotatable shaft fixed thereto, a ribbon spool journaled on said shaft, a peripheral member fixed to the spool to rotate therewith, means cooperating with the periphery of said member for constantly tensioning the spool, normally ineffective locking means adapted to engage the periphery of said member, and means for rendering said locking means effective.

20. In a ribbon spool assembly, the combination with a supporting frame, of a non-rotatable shaft fixed thereto, a plurality of ribbon spools journaled on the shaft, a plurality of members respectively connected to the spools to rotate therewith and provided with serrated peripheries, means respectively cooperating with the peripheries of the members for constantly tensioning the spools, normally ineffective locking means adapted to respectively engage the peripheries of the members to retain the spools against rotation, and means for rendering said locking means effective.

21. In a ribbon spool assembly, the combination with a supporting frame, of a non-rotatable shaft fixed thereto, a plurality of ribbon spools journaled on the shaft, a plurality of members respectively connected to the spools to rotate therewith and provided with serrated peripheries, means respectively cooperating with the peripheries of the members for constantly tensioning the spools comprising a plurality of levers, serrated rollers respectively journaled on the levers for engaging the serrated peripheries of said members, and springs connected to the levers for retaining the rollers in tensioning engagement with the serrated peripheries of the members, normally ineffective locking means adapted to respectively engage the peripheries of the members to retain the spools against rotation, and means for rendering said locking means effective.

22. In a ribbon spool assembly, the combination with a supporting frame, of a non-rotatable shaft fixed thereto, a plurality of ribbon spools journaled on the shaft, a plurality of members respectively connected to the spools to rotate therewith and provided with serrated peripheries, means respectively cooperating with the peripheries of the members for constantly tensioning the spools, normally ineffective locking means adapted to respectively engage the peripheries of the members to retain the spools against rotation and including a plurality of levers, locking pawls respectively connected to the levers for engaging the serrated peripheries of the members, means cooperating with the levers for normally retaining said pawls in ineffective locking positions, and means for rendering said locking means effective.

23. In a ribbon spool assembly, the combination with a supporting frame, of a non-rotatable shaft fixed thereto, a plurality of ribbon spools journaled on the shaft, a plurality of members respectively connected to the spools to rotate therewith and provided with serrated peripheries, means respectively cooperating with the peripheries of the members for constantly tensioning the spools comprising a plurality of levers, serrated rollers respectively journaled on the levers for engaging the serrated peripheries of said mem-

bers, and spring connected to the levers for retaining the rollers in tensioning engagement with the serrated peripheries of the members, normally ineffective locking means adapted to respectively engage the peripheries of the members to retain the spools against rotation and including a plurality of levers, locking pawls respectively connected to the levers for engaging the serrated peripheries of the members, means cooperating with the levers for normally retaining said pawls in ineffective locking positions, and means for rendering said locking means effective.

24. In a ribbon spool assembly, the combination with a supporting frame, of a non-rotatable shaft fixed thereto, a plurality of ribbon spools journaled on the shaft, a plurality of members respectively connected to the spools to rotate therewith and provided with serrated peripheries, a bearing rod supported on the frame beyond the peripheries of the members and disposed in parallelism with the spool-supporting shaft, a plurality of spool tensioning levers fulcrumed on the bearing rod and respectively engaging the serrated peripheries of the members, a plurality of locking pawls fulcrumed on the bearing rod for cooperation with the respective serrated peripheries of the members, a coil spring connecting each tension lever and the associated locking pawl for normally urging the locking pawl into locking engagement with the associated member, a universal frame fulcrumed on the bearing rod and common to all of the locking pawls, a spring connecting the universal frame and the supporting frame for normally retaining the locking pawls in ineffective locking positions, and a manually operable lever connected to the universal frame for moving the latter against the tension of its spring whereby the locking pawls will be moved into effective locking engagements with the members by the springs which connect the tension levers with the locking pawls.

25. In a ribbon spool assembly, the combination with a supporting frame, of a non-rotatable shaft fixed thereto, a ribbon spool journaled on said shaft, a peripheral member fixed to the spool to rotate therewith and provided with a serrated periphery, means cooperating with the periphery of said member for constantly tensioning the spool, normally ineffective locking means adapted to engage the periphery of said member, means for rendering said locking means effective, and manually operable means for releasing the tensioning means from engagement with the serrated periphery of said member.

26. In a ribbon spool assembly, the combination with a supporting frame, of a non-rotatable shaft fixed thereto, a plurality of ribbon spools journaled on the shaft, a plurality of members respectively connected to the

the spools to rotate therewith and provided with serrated peripheries, means respectively cooperating with the peripheries of the members for constantly tensioning the spools, 5 normally ineffective locking means adapted to respectively engage the peripheries of the members to retain the spools against rotation, means for rendering said locking means effective, and manually operable means for simultaneously releasing all tensioning means 10 from engagements with said members.

27. In a ribbon spool assembly, the combination with a supporting frame, of a non-rotatable shaft fixed thereto, a plurality of 15 ribbon spools journaled on the shaft, a plurality of members respectively connected to the spools to rotate therewith and provided with serrated peripheries, means respectively cooperating with the peripheries of the 20 members for constantly tensioning the spools, normally ineffective locking means adapted to respectively engage the peripheries of the members to retain the spools against rotation, means for rendering said locking means effective, a rockable cam shaft located beyond 25 the peripheries of the members and disposed in parallelism with the spool-supporting shaft, operative connections between the tensioning means and the cam shaft and between the locking means and the cam shaft, and a 30 manually operable hand/lever fixed to the cam shaft for rocking the same to effect a release of all tensioning means and to further retract all of the locking means.

28. In a ribbon spool assembly, the combination with a supporting frame, of a non-rotatable shaft fixed thereto, a plurality of ribbon spools journaled on the shaft, a plurality of members respectively connected to the spools to rotate therewith and provided with serrated peripheries, means respectively cooperating with the peripheries of the members for constantly tensioning the spools comprising a plurality of levers, serrated rollers 45 respectively journaled on the levers for engaging the serrated peripheries of said members, and springs connected to the lever for retaining the rollers in tensioning engagement with the serrated peripheries of the 50 members, normally ineffective locking means adapted to respectively engage the peripheries of the members to retain the spools against rotation, means for rendering said locking means effective, and manually operable means for releasing the tensioning means 55 from engagements with the serrated peripheries of said members.

29. In a ribbon spool assembly, the combination with a supporting frame, of a non-rotatable shaft fixed thereto, a plurality of ribbon spools journaled on the shaft, a plurality of members respectively connected to the spools to rotate therewith and provided with serrated peripheries, means respectively 60 cooperating with the peripheries of the mem-

bers for constantly tensioning the spools, normally ineffective locking means adapted to respectively engage the peripheries of the members to retain the spools against rotation and including a plurality of levers, locking 70 pawls respectively connected to the levers for engaging the serrated peripheries of the members, means cooperating with the levers for normally retaining said pawls in ineffective locking positions, means for rendering 75 said locking means effective, and manually operable means for releasing the tensioning means from engagements with the serrated peripheries of said members.

30. In a ribbon spool assembly, the combination with a supporting frame, of a non-rotatable shaft fixed thereto, a plurality of ribbon spools journaled on the shaft, a plurality of members respectively connected to the spools to rotate therewith and provided with serrated peripheries, a bearing rod supported on the frame beyond the peripheries of the members and disposed in parallelism with the spool-supporting shaft, a plurality of spool tensioning levers fulcrumed on the bearing rod and respectively engaging the serrated peripheries of the members, a plurality of locking pawls fulcrumed on the bearing rod for cooperation with the respective serrated peripheries of the members, a coil spring 95 connecting each tension lever and the associated locking pawl for normally urging the locking pawl into locking engagement with the associated member, a universal frame fulcrumed on the pivot shaft and common to all 100 of the locking pawls, a spring connecting the universal frame and the supporting frame for normally retaining the locking pawls in ineffective locking positions, a manually operable lever connected to the universal frame 105 for moving the latter against the tension of its spring whereby the locking pawls will be moved into effective locking engagements with the members by the springs which connect the tension levers with the locking pawls, 110 and manually operable means for releasing the tensioning means from engagements with the serrated peripheries of said members.

31. In a manifolding typewriter, a rotatable ribbon spool including a peripheral 115 member rotatable therewith, ribbon feeding means, means cooperating with the periphery of said member for tensioning the feeding movement of said ribbon, normally ineffective means adapted to cooperate with the periphery of said member to lock the spool against feeding movement, and means for rendering said locking means effective.

32. In a manifolding typewriter, a rotatable ribbon spool including a disc rotatable 125 therewith and having a serrated periphery, ribbon feeding means, means cooperating with the periphery of said disc for tensioning the feeding movement of said ribbon, a normally ineffective clutch pawl adapted to 130

cooperate with the periphery of said disc to lock the spool against feeding movement, and means for rendering said locking means effective.

5 33. In a manifolding typewriter, a rotatable ribbon spool including a peripheral member rotatable therewith, ribbon feeding means, means normally cooperating with the periphery of said member for tensioning the

10 feeding movement of said ribbon, normally ineffective means adapted to cooperate with the periphery of said member to lock the spool against feeding movement, means for rendering said locking means effective, and means

15 for releasing said tensioning means from said member.

34. In a manifolding typewriter, a plurality of ribbon spools individually rotatable about a common axis and each including a

20 peripheral member rotatable therewith, ribbon feeding means, separate means respectively cooperating with the peripheries of the members for individually tensioning the feeding movements of the ribbons, normally in-

25 effective means adapted to cooperate with the peripheries of the members to lock the spools against feeding movements, means for rendering said locking means effective, and means for releasing simultaneously all of the tensioning

30 means from the members.

35. In a ribbon spool assembly, the combination with a rotatable ribbon spool including a member having a serrated periphery, a tension roller having a serrated periphery con-

35 sistent with and normally engaged with the serrated periphery of the member to tension the spool against feeding rotation, normally ineffective means including a locking pawl having a serrated surface consistent with and

40 adapted to engage the serrated periphery of the member to lock the spool against feeding rotation, and means for rendering said locking means effective.

In testimony whereof, we have hereunto
45 subscribed our names.

GEORGE F. HANDLEY.
LEWIS C. MYERS.
